EDWARD S. HALSEY, OF WASHINGTON, DISTRICT OF COLUMBIA

STEAM-HEATING SYSTEM

Application filed February 19, 1929. Serial No. 341,097.

The invention particularly concerns two pipe steam heating systems of the low constant pressure type in which the radiators are entirely controlled by suitably proportioned individual admission valves in connection therewith.

The main object of this invention is to overcome the numerous circulation troubles common to two pipe systems, which are largely caused from the usual practice of discharging both the air and the water through the return pipes. This causes air binding of the ordinary system, especially when not perfectly graded, and necessitates numerous expensive automatic appliances in the piping and boiler room to alleviate same, which are liable to many disorders, all of which are eliminated by this new system.

The invention consists in the features and combination and arrangement of parts hereinafter described and particularly pointed out in the claims.

In the accompanying drawings:

Fig. 1 is a side elevation of a system embodying my invention.

Fig. 2 is an end view of one of the radiators.

Fig. 3 is a view of an adjustable heat deflector.

Fig. 4 is a view of a modified form of U trap.

Fig. 5 is a view showing the manner of attachment of the vent pipe to the steam inlet pipe.

In these drawings, 1 indicates the steam generator, which may be provided with the usual damper, and steam is supplied to the radiators, only two of which are shown, by pipes 7, 8. A supply main is shown at 9.

Each radiator preferably has a return coupling 10 connecting with the return pipes 11 and 12, by which the condensation water is returned from the radiators to the boiler 1.

Each radiator at its upper part preferably has mounted directly thereon a thermostatic modulating valve. This is shown generally at 13. Each of these valves controls the supply of steam to the radiator upon which it is mounted. These valves have their thermostatic elements or cells as at 14 exposed to

the room temperature and the valves are gradually closed or opened according as the temperature of the room rises or falls.

While various forms of thermostatic elements or valve mechanism may be employed, I preferably employ a form of these elements like that disclosed in application filed by me No. 333,604, January 19th, 1929, in which the cell 14 contains a fluid, such as an example, as kerosene, expansible under a rise of temperature, said fluid controlling certain valve connections by which the valve is set close to or upon its seat to cut off the steam supply to the radiator on a prescribed rise of room temperature, and by which the valve is retracted from its seat to supply steam to the radiator upon a drop in room temperature.

It is customary to provide automatic traps to prevent the steam from blowing from the radiator into the returns, such means being mounted in connection with the return fittings at the outlet leading from the radiator. It is also customary to discharge the air from the radiators with the water directly into the return lines, which frequently causes air binding therein.

My system provides means to prevent this binding, even if the air is discharged into the returns.

With my improvement I dispense with thermostatic steam traps on the returns entirely, so as to leave a free open discharge for water at all times from each radiator into the returns, and I prefer not to discharge the air with the water.

In carrying out my invention, I preferably provide a pipe connection 15 extending from the point where the air vent of the radiator is usually placed back to the thermostatic cell 14 controlling the steam inlet valve.

The point where the usual air vent is placed is at α . This is on the opposite side of the radiator from the location of the steam inlet valve at 13 and at the upper part of the last radiator section and it is at this point α that the pipe 15 is preferably connected.

While the radiator is being charged with steam, the air therein will be discharged through the pipe 15. Its outlet end 15 α is provided with a discharge opening sufficiently

large to permit the air to escape rapidly, so that the radiator will be charged with steam as rapidly as possible.

large to vent the air freely. This last section of the radiator is the last one to receive steam and when the steam reaches the point x , if some preventive means were not made, it 5 would soon blow to waste through the return connection 10. With my preferred form, as soon as the steam reaches the point x in the last section of the radiator, it will flow through the pipe 15 and impinge against the 10 thermostatic cell 14, quickly expanding the fluid therein sufficiently to partially close its valve upon its seat to cut down or cut off the supply of steam to that particular radiator upon which the said cell and its valve are 15 mounted. The discharge end of the pipe 15 is turned upwardly to deliver the steam against the lower side of the cell 14, so that the heat will act not only upon the said lower side but will rise along the lateral sides of the cell to 20 get a quick action. When the supply of steam is cut down in quantity, so that it no longer issues from pipe 15, the thermostat will open the steam inlet valve gradually to supply sufficient steam to bring the room up to temperature, but in case the room is very cold, 25 the above described action may be repeated several times before the room temperature is sufficiently high to cause the throttling down of said valve so as to only partially fill the 30 radiator.

As above stated, the outlet opening of the vent pipe 15 at $15a$ is large enough to provide a free vent, as distinguished from the ordinary restricted vent as customarily used. 35 This free vent will insure the escape of air from the radiator and from the system and it will insure quick response of the thermostat in closing the steam inlet valve to the proper degree when the prescribed volume of steam 40 has entered the radiator. With my improvement, as in the application above mentioned, each radiator can be regulated by hand individually by rotating the thermostatic mechanism at 14, to close or open the steam inlet 45 valve. In the drawing I indicate at 16, 17 plates associated with the thermostatic mechanism which serve as heat shielding means, to prevent heat radiated from the valve casting from reaching the thermostatic cell 14, 50 these plates being similar to those disclosed in said application.

I may employ a restricted vent located at a high point in the system for venting air therefrom. Such vents may be at the upper 55 ends of the pipes 11, 12.

At 19 I employ an adjustable heat deflector. This consists of a disc or plate set at an inclination and carried by a collar or holder 20, which may be affixed to the steam supply 60 pipe by a set screw 21, so that by loosening this screw the collar can be turned about the steam pipe and fixed in any position to which it may be adjusted. In this way the inclined plate may be set to deflect the rising currents 65 of air in respect to the cell 14, it being noticed

that said deflector is arranged at a lower level than the cell and, according to its adjustment, it will direct the air current either to or away from the cell.

The vent pipe 15 extends between the columns of the radiator, as shown, or otherwise. 70

My invention avoids the use of thermostats at the return bends and automatic air release valves disposed at various parts of the system. It avoids the troubles resulting from improper engineering in the grading of pipes and connections. 75

At 22 I show an individual riser sump for catching sediment, such as rust or dirt. Into this sump the lower end of the return riser 11 or 12 is located. This pipe 12 terminates slightly below the water level $a-a$ in the sump. This water level is determined by the location of the return main 23. This pipe connects with the sump at a point intermediate the upper and lower ends thereof. The sump is open at its upper end for the free venting of air from the system at this point. Its body is of sufficiently large diameter to facilitate the free separation of the air from the water. It may have a removable bottom by which the sediment may be removed, or it may be completely removed to give free access to the open ends of risers and laterals, by simply disconnecting the unions 25 and 25. 80

By removing the individual riser sump the sediment therein can be dumped out and the laterals, as 28, can be cleared of any obstruction, either by running a rod therethrough or by blowing out said lateral. 85

Instead of this form of sump, the form shown in Fig. 4 may be employed. In this form, the lower end of the return riser pipe extends into the chamber 22a. This is closed at its top and it has a removable bottom for cleaning. It has a fitting 23b connected therewith for the return pipe 23a and on this fitting there is an outlet vent for air consisting of the pipe 23c, which is open at its upper end. In Figure 1, the main pipe for returning the condensation water to the boiler is shown at 23d. 90

At 24, at the top of the return pipe 23d, I show a regulator for the damper of the boiler consisting of an open top common sump for all the returns in the system, for the venting of air. This chamber contains a float 25 subject to the fluctuations of water level resultant from variations of the boiler pressure. When the pressure rises above the prescribed degree, the float rises and allows the damper 2 to close. This is done through a connection 26 which runs over pulleys 27 from the piston to the damper. 95

This main sump gives a final separation of air and dirt from the system before the return water reaches the boiler. The free open vent at the top of this common sump around its piston prevents air binding or trapping of the system. 100

I show at 28 a low pressure blow-off pipe extending from the main steam supply pipe 9, into a chamber 29 which is filled with water to a predetermined level, having a static 5 head slightly less than that between the water in the boiler and the top of return sump 24, so that the boiler will blow off any excess steam into this tank of water before sufficient steam pressure has been generated to 10 cause the water to overflow at the return sump.

Several advantages are gained by this low pressure blow-off device, namely, reliability of action, the basement is not filled with 15 steam, and a great racket is made to attract the attention of an attendant to the fact that the damper is not properly checking the fire.

The blow-off pipe reaches to near the bottom of this chamber and discharges into the 20 body of water.

My system works best on a pressure of about one pound.

At each of the return fittings 10 I preferably employ a water seal indicated at 30. 25 These water seals are to discourage air from the radiators passing into the return piping. They are fitted with removable bottoms to allow them to be cleared of sediment.

I do not limit myself to the relative location and arrangement of the vent and the 30 thermostatic valve, as other arrangements of said parts may be used without departing from the spirit of the invention as defined by the scope of the appended claims.

35 In this system the location of any stoppage in the return pipes is self-indicating and readily removed, by virtue of the individual free open separator sumps at the bottom of each return riser in combination with the 40 common open return sump pot, for the group of return laterals, arranged over and discharging vertically to the boiler return pipe; also smaller return pipes may be used throughout the return system without a possibility 45 of air binding. Also on account of a free open air vent on each radiator, smaller steam supply pipes may be effectively used as practically no pressure is required to push the air out of the radiators.

50 I claim:

1. In combination with a steam radiator, a steam inlet valve, thermostatic means for controlling said valve according to room temperature, and a vent to atmosphere for 55 the radiator, said vent discharging upon the thermostatic means, substantially as described.

2. Apparatus according to claim 1, in which the vent comprises a pipe having its 60 discharge end directed against the exterior of the thermostatic means to discharge steam freely onto said means.

3. Apparatus according to claim 1, in which the vent comprises a pipe extending 65 from the radiator at a point thereon op-

posite the side of said radiator at which the inlet valve is located and discharging against the exterior of the thermostat located at the inlet side of the radiator, substantially as described.

4. Apparatus according to claim 1 in which the vent comprises a pipe extending from the last section of the radiator back between the columns of the radiator to the thermostat at the inlet side of the radiator.

5. Apparatus according to claim 1, in which the inlet valve is manually operable by turning the thermostatic means.

6. In combination with a radiator and a thermostatically controlled inlet valve therefore, a deflector to deflect the heat from the thermostat, said deflector consisting of an inclined plate arranged below the thermostat substantially as described.

7. Apparatus according to claim 6, in which the deflector consists of a plate inclined relative to and adjustable about a vertical axis to deflect the heat in different directions.

8. Apparatus according to claim 6, in which the inclined deflector is mounted on the steam supply pipe leading to the radiator and means for setting said plate in different positions about said supply pipe.

9. In combination with a steam radiator and its steam inlet valve, a thermostat arranged coaxially with the valve and comprising a cell exposed to the room temperature and serving as a handle for adjusting the valve and a vent for the radiator discharging to atmosphere and upon said cell, substantially as described.

In testimony whereof I affix my signature.
EDWARD S. HALSEY.
